SAFETY RAZOR

George R. Bott, Stamford, Conn.; The Stamford Trust Company executor of said George R. Bott, deceased

Application July 11, 1936, Serial No. 90,060

21 Claims. (Cl. 30—43)

The present invention relates to safety razors and has for an object to provide an improved construction of mechanical or motor operated safety razor adapted particularly for close shaving without the use of soap, cream and the like.

Another object of the present invention is to provide a mechanical safety razor wherein the cutting is effected by a shearing action as in the operation of shears and wherein the cutting edges 5 are completely enclosed or encased and only rounded edges are presented to the exterior of the razor for contact with the skin and surrounding objects.

The invention also embodies certain detailed 10 characteristics in the structure of the razor adapting it for easy operation by an electrical motor so as to combine with the motor in providing a body portion serving as a handle for the razor and enclosure for the motor and other parts 15 of the device, all of which may be readily manufactured and as easily assembled.

The invention has for a still further object a 20 peculiar combination of a guard, a comb and a cutter housed between them and wherein the cutter and comb teeth are relatively beveled, inclind and spaced apart with respect to the teeth of the separate elements to obtain a relatively close dry shave by a shearing or clipping action 25 which takes place at the beveled juncture of the comb and cutter, and wherein the cutting edge 30 may be continuous or toothed and at the same time be completely housed, and encased by the guard and comb.

With the foregoing and other objects in view, 35 the invention will be more fully described hereinafter, and will be more particularly pointed out in the claims appended hereto.

In the drawings, wherein like symbols refer to 40 like or corresponding parts throughout the several views.

Figure 1 is a longitudinal section taken through a power operated razor embodying the features of the present invention.

Figure 2 is a similar view taken on the axis 45 2—2 of Figure 1 at right angles thereto.

Figure 3 is a transverse section taken through the inner end of the razor on the line 3—3 of Figure 1 and looking toward the vibrator elements of the motor.

Figure 4 is a transverse section taken through the outer end portion of the razor on the line 4—4 of Figure 2 and looking toward the flexible motion converting brushes.

Figure 5 is a fragmentary outer end view of 55 the razor, looking toward the guard and showing

the beveled arrangement of the cutter and comb with respect to the exterior surface of the guard.

Figure 6 is a detail plan view of the inner end cap removed from the razor casing.

Figure 7 is a fragmentary enlarged plan view 5 of a portion of the outer edge razor structure showing the guard, cutter and comb in their relative positions and with the exposed edges of the cutter rounded and with the cutting edges disposed against the comb and being inclined with respect to the teeth of the comb.

Figure 7a is a section taken on line 7a—7a of Figure 7.

Figure 8 is a transverse section taken through the cutter and comb on line 8—8 of Figure 7 15 showing the transversely inclined throats between the cutter and comb teeth.

Figure 9 is an enlarged transverse section taken through the razor structure as applied to the flesh, the section being taken substantially on the line 9—9 of structure shown in Figure 7, and

Figure 10 is a diagram of a motor circuit which may be used for operation of the razor.

Referring now to the drawings, and first to Figures 1 to 4, a casing or housing 20 is adapted 25 to carry therein the electric motor or other operating device for the razor. This casing is made of suitable length and at its outer end portion is preferably enlarged and flared and provided with a plurality of flutes or ribs 21 to facilitate 30 holding or grasping of the razor for operation. The casing or housing 20 is provided at its lower end with a removable cap 22 of any suitable construction and configuration to provide a continuation of the housing and to facilitate access to the 35 motor and other parts of the casing.

The upper end of the housing 20 is relatively flat and serves as a support for an annular comb 23 secured to the casing by screws 24 or the like. The comb 23 has outstanding teeth 25 which project beyond the casing 20 and are adapted for direct contact with the skin or flesh over which the razor is operated. The upper end of the casing 20 is recessed to provide a cavity or chamber 26 within which is placed an internally toothed ratchet ring 27 provided with a hub 28 for supporting the ring in the recess 26. The hub 28 is rotatably mounted on a pin 29 which is recessed and internally threaded at its outer end for the reception of a correspondingly threaded stud 30 which has a kerfed head 31 abutting the outer end of the hub 28 and which carries as a part thereof a guard plate 32 which in the combination is an integral part of head 31. The guard 32 may be given any suitable configura- 50 55

tion. In the present instance it is shown as of conical form and the hub 28 extends up into the conical structure to bear against and support the guard over the outer end of the razor.

5 Interposed between the guard 32 and the comb 23 is a cutter 33. The cutter 33 may be of any suitable configuration and at its outer marginal edge is adapted to lie flat against the outer side 10 of the comb 23. The cutter 33 is mounted on the hub 28 and by pin 28^a is coupled for turning therewith. A radial spring spider 34 fitted over the hub and held in yielding engagement with the cutter 33 by a lock or snap ring 35 carried by the hub 28 as shown. Rotation of the hub 15 28 with its ratchet ring 27 thus causes the cutter 33 to turn against the comb 23 and free from the guard 32. The cutter 33 is pressed against the comb 23 and is in shearing action therewith.

While any suitable means may be employed for 20 rotating the cutter disc 33, in the present instance a vibrating or reciprocating electric motor is illustrated with flexible brushes cooperating with the ratchet ring 27 to convert the vibratory action of the motor into rotary motion of the 25 hub and cutter. This type of motor is disclosed and claimed in my co-pending application.

For the purpose of illustration, the motor referred to comprises a field coil 36 which at its inner end is provided with a spacing bracket 37 to which is secured a micarta base disc or plate 38 constructed and proportioned to fit in the inner end and the housing 20 and against the flange of the cap 22. The bracket 37 and disc 38 thus hold the magnet 36 from moving within 35 the casing.

The upper end of the field coil or magnet 36 is provided with a pair of spring arms 39 having crimped or toothed portions at their outer ends adapted to engage the opposite sides of a shouldered crossbar 40. The crossbar extends from one side of the housing to the other. The crossbar 40, in the embodiment, is an integral part of the housing, as shown. These spring arms 39 snap into the opposite shouldered sides of the crossbar 40 beneath the hub 28. The snap spring arms 39 serve to lock the motor in position on the crossbar 40. On the end of the magnet 36 is mounted a pair of vibrating armatures 41. The armatures 41 extend lengthwise of the opposite sides of the magnet 36 and at their lower ends are reduced and extend through slots 42 provided in the base disc 38, as shown in Figure 1. These armatures 41 have curved supporting springs 43 at their upper ends so that the armatures 41 may swing in a flatwise direction on the springs 43 under vibratory action of the magnet 36. The lower ends of the armatures 41 are interconnected by spring 44 which is arched toward one side of the housing or cap and carries a vibrator point 45 cooperating with an adjustable screw point 46, the latter being mounted in a post 47 secured to and depending from the base disc 38. The post 47 is connected in an electric circuit, in which a condenser 48 is included which may be mounted 50 upon the outer side of the base disc 38 within the bracket 37 and suitably connected to the magnet coil 36 as shown in Figure 10. Current may be introduced to the motor in any suitable manner such as by an electric cord or cable 49 55 the wires of which lead to separable connector parts 50 mounted within the detachable cap 22 and which engage correspondingly separable connector parts 51 which are carried upon the lower side of the base disc 38. Thus when the cap 22 60 is snapped up into position on the housing 20

the separable elements 50 and 51 of the connectors are automatically brought into engagement with each other so as to complete the circuit wiring through the motor.

Each armature 41 is provided with a bracket 52. The bracket 52 extends in an edgewise direction from the adjacent armature 41, and preferably adjacent the spring portion 43 of the armature. The bracket 52 is bent at right angles about the side of the magnet 36 and extends 10 outwardly into the recess 26 and into the cavity of the ratchet ring 27. Brush holders 53 are mounted upon the outer ends of the brackets 52 and carry flexible brushes 54 of flexible bronze wire or the like which are adapted to engage and 15 operate against the internal ratchet teeth of the ring 27.

With reference to Figures 5 to 9, it will be noted that the guard 32, the teeth of the cutter 33, and the teeth 25 of the comb are all beveled or 20 lie at their outer exposed faces in substantially a common plane. From Figure 7 particularly it will be noted that the teeth of the cutter 33 have rounded or non-cutting outer edges 33^a while their cutting or shearing edges 33^b are disposed 25 inwardly of the cutter teeth and lie and operate against the lower or edged half of the teeth 25 of the comb. It will be noted from Figure 7 that the bevelling is on the front surfaces of the cutter and comb. This is also clearly shown in Figure 9. 30

In this manner there are no exposed cutting edges exteriorly of the razor and consequently the razor is rendered safe and there is no chance of the user nicking or scraping the skin during use of the razor. Furthermore, the cutting 35 edges 33^b operating against the inner adjacent face of the comb are maintained at all times in a sharpened or properly ground position so that practically no resharpening or these razor elements is required. It will also be noted from 40 Figure 7 that the cutting edge of the cutter teeth 33 is disposed at a different angle from the cutting edge of the comb teeth 25 with which the cutter teeth cooperate so that in operation there is a shearing cutting action between the teeth. 45 Furthermore, as shown in Figure 8 particularly, the throats 55 between the cutter teeth 33 and comb teeth 25 are diagonally or transversely inclined so as to increase the holding effect on the entrapped hair which has entered between 50 the comb and cutter teeth.

In operation, the motor vibrates the armatures 41 which in turn vibrate the bracket arms 52 and the brushes 54. The result is that the vibration of the brushes which operate against 55 the internal ratchet ring 27 causes the latter to turn slowly, such as in the direction shown by the arrow in Figure 4. The rotation of the ring 27 turns its hub 28 and consequently turns the cutter 33 which is mounted on the hub. 60

As shown in Figure 9, the inner faces of the comb 23 and cutter 33 abut one another at least near their outer marginal edges. It will also be observed that the comb teeth 25 and the cutter teeth 33 are provided with their sharp or shearing edges in the plane of contact of the comb and cutter and consequently these comb and cutter teeth move with a point of contact continuously advancing throughout the throats of the teeth during the relative turning of the cutter to comb. It will also be noted that the comb and cutter teeth, at the exposed or outer side of the razor, are beveled to lie in substantially the same plane and also with reference to the inclined outer surface of the guard 32 65

so that there is a continuous smooth and substantially uninterrupted non-cutting surface for contact with the skin or flesh, and it is only the hairs which project from the surface that enter 5 between the teeth 25 of the comb and finally into the throats between the cutter teeth 33 which are severed or cut by the shearing action which takes place only in the plane of contact of the inner abutting faces of the comb and 10 cutter.

When the razor is applied to the skin the rounded or non-cutting exposed edges of the comb and cutter teeth only are brought into contact with the flesh while the inner abutting or 15 contacting shearing edges of the comb and cutter teeth are brought into close proximity to the flesh incident to the beveled construction of the teeth so that the shearing or cutting action may take place immediately adjacent the extreme 20 point or outer ends of the cutter teeth to shear the hairs close to the flesh. The beveling of the superposed comb cutter and guard provides the gradual receding of the exposed portions of the teeth of the comb and cutter so as to bring 25 the flesh into close relation to the shearing edges without danger of injury to the flesh but at the same time to insure the close cutting of the hairs.

One of the advantages of this razor is to 30 assemble it rapidly, all parts snapping together except the guard or nose, which, in the embodiment, is screwed on. The assembly of each razor is approximately one minute. There is no soldering or fitting of parts.

35 It is obvious that various changes and modifications may be made in the details of construction and design of the above specifically described embodiments of this invention without departing from the spirit thereof, such changes and modifications being restricted only by the scope of the following claims.

What is claimed is:

1. In a motor-actuated razor, curved comb and 40 razor cutter members mounted in parallel relation and having cooperative radial edge teeth 45 in shearing contact on adjacent sides, the teeth of at least one of said members being cut on a transverse spiral and the teeth of both of said members being transversely beveled in continuity, to produce cooperative shearing edges 50 on teeth which diminish in thickness outwardly thereof, with the free radial ends of the teeth of the cutter member adjacent the comb having substantially zero thickness.

55 2. A razor cutter comprising a circular body having parallel sides and edge teeth spirally cut across the body between the sides, said teeth being beveled from one side of the body toward the other across the pitch of the spiral cuts to produce on such beveled side angular cutting edges on teeth diminishing in thickness toward their cutter free ends.

60 3. A razor cutter comprising a body having parallel side surfaces and edge-projecting teeth with surface-rounded skin-engaging outer free 65 ends, said teeth being curvingly cut across the body between said side surfaces and beveled from one side surface toward the other across the pitch of the spiral cuts to produce on such beveled side angular cutting edges on teeth gradually diminishing in thickness to said outer free ends.

65 4. A shaving machine carrying a nose cap in front of the machine, an actuatable cutter behind the cap and a comb behind the cutter, said cap having a backwardly and outwardly sloping por-

tion, peripheral edges on the cutter and comb respectively forming a continuation of the backwardly and outwardly sloping portion of the cap and comprising spaced apart teeth formed on and between the cutter and comb for shearing 5 hair entering between these parts, the spaces between the comb teeth being open through the back of the comb for the reception of hair to be sheared, and said teeth through the thickness of the cutter and comb respectively being cut 10 at an angular pitch to give keen cooperating cutting action and also self-sharpening action.

5. In a safety razor, a skin-contacting guard, a stationary skin-contacting member having edge teeth, and a rotatable skin-contacting member 15 having edge teeth mounted between the guard and the stationary member for movement relative to the stationary member and over the skin, the outer skin-contacting sides of the guard and members lying in substantially a common 20 plane oblique to the axis of the rotatable member, the teeth of the rotatable member having their outer edge portions beveled in relation to the oblique plane to admit close proximity of the inner sides of the rotatable member to the 25 skin when the razor is in use and the teeth of the rotatable member having dulled non-cutting edges at their outer sides to prevent injury to the skin and having adjacent contacting flat surfaces terminating in cooperating shearing 30 edges at the sides of the teeth for cutting hairs entering the throats of said teeth and the teeth of the stationary member by relative movement between the members.

6. In a safety razor, a guard, a stationary 35 member having edge teeth, and a skin-contacting movable member having edge teeth mounted between the guard and the stationary member for movement relative to the stationary member, the outer skin contacting sides of the guard and 40 members in any transverse section lying in substantially a common plane oblique to the plane of movement of the movable member, said teeth having diagonally disposed throats and their outer edge portions being beveled, and said members 45 having adjacent contacting flat surfaces terminating in cooperating shearing edges at the sides of the teeth for cutting hairs entering the throats of the teeth.

7. In a safety razor, a guard, a stationary 50 member having edge teeth, and a skin contacting movable member having edge teeth mounted between the guard and the stationary member for movement relative to the stationary member, the outer skin-contacting sides of the guard and 55 members in any transverse section lying in substantially a common plane oblique to the plane of movement of the movable member and having their outer edge portions beveled in relation to the oblique plane to admit close proximity of the 60 inner sides of the movable member teeth to the skin when the razor is in use and the teeth of the members having dull, non-sharpened edges at their outer sides and having adjacent contacting flat surfaces terminating in cooperating 65 shearing edges at the sides of the teeth for cutting hairs entering the throats of the teeth by relative movement between the members, corresponding lateral sides of adjacent teeth of both cutting members upon alignment of the teeth 70 being in a plane inclined to the cutting plane.

8. In a safety razor, a stationary skin contacting guard, a movable skin contacting member having teeth at its edge and a stationary skin contacting member having edge teeth, said 75

guard and members being disposed in superposed relation, the skin contacting surfaces of the guard, movable member, and stationary member in any transverse section being in a plane to 5 present a flat skin contacting surface, the abutting inner sides of the teeth of the members being flat and terminating in shearing edges for cutting hairs by a shearing action upon relative movement between the teeth, corresponding lateral sides of adjacent teeth of both cutting members upon alignment of the teeth being in a plane inclined to the cutting plane.

9. A razor comprising a face-contacting cutter, a second cutter, each cutter having teeth 15 with intervening spaces adapted to receive the hair to be cut, means for moving the face-contacting cutter, motor means, means vibrated by said motor means, and means translating the vibratory movement of said vibrated means into 20 relatively slow movement of said cutter-moving means, said moving means, motor means, vibrated means, and translating means being substantially axially arranged in respect to the plane of movement of the moving cutter, whereby the 25 face-contacting moving cutter is subjected to a relatively low speed.

10. In a razor, the combination of a plurality of spaced members each having at least three sides, a smooth uncutting side adapted to be 30 placed upon the skin to be shaved and two sides having their planes intersecting to form a cutting edge, a second plurality of spaced members normally disposed upon said first-named members and each having at least two sides, with 35 their planes intersecting to form a cutting edge, all of said cutting edges being substantially in one and the same plane, and in spaced planes at an acute angle thereto, and means moving the acute angle cutting edges of the members 40 in respect to each other, whereby the cutting edges incline in respect to each other during their cutting action.

11. A razor comprising two discs contacting with each other, each provided with a plurality 45 of teeth having intervening spaces therebetween, said teeth extending outwardly from the peripheral circumference of said discs, the teeth and spaces of one disc registering with the teeth and spaces of the other disc when in non-cutting 50 position, one side of each plurality of teeth forming skin-contacting surfaces in a conical surface the apex of which is in the axis of rotation of said discs, and the two sides adjacent said skin-contacting sides of each plurality of 55 teeth being inclined to the plane of rotation of said teeth, said lateral sides of each plurality of teeth having cutting edges formed by the intersection of planes spaced apart a distance equal to the width of the teeth, forming an acute angle with the plane of rotation of said teeth, means rotating one disc in respect to the other, and comb portions on one set of plurality of teeth extending beyond the cutting edges thereof, whereby the acute angle cutting edges of one 60 plurality of teeth move scissor-like in shearing action against the acute angle cutting edges of the other set of plurality of teeth to cut hair entering the spaces between the teeth of both discs, the spaces between the comb portions of the 65 teeth being adapted to comb the hair in proper 70 position for said shearing action.

12. A razor comprising a skin contacting member having cutting edges, and having a skin 75 contacting side flush with the skin, the hairs of which are intended to be cut, said cutting

edges forming with the skin-contacting side an acute angle, and said cutting edges extending to the apex of said angle, a second member on the off-skin side of said first member and having cutting edges, the cutting edges of the respective members being inclined to each other during cutting action, means for moving the skin contacting member on the skin, and in respect to the second member to cut the hairs of the skin between the cutting edges, and extensions 10 on the second member having skin contacting surfaces in the same plane which passes through the plane of the skin contacting side of the first member.

13. A razor comprising a skin contacting member having cutting edges, and having a skin contacting side flush with the skin, the hairs of which are intended to be cut, a second member on the off-skin side of said first member and having cutting edges, the cutting edges of the 20 respective members being inclined to each other during cutting action, and means for moving the skin contacting member on the skin and in respect to the second member, to cut the hairs of the skin between the cutting edges, extensions 25 on the second member having skin contacting surfaces in the same plane which passes through the plane of the skin contacting side of the first member, and a skin contacting guard, the movable first member being disposed between the 30 guard and extensions.

14. A razor comprising a movable skin contacting member having a bottom plane surface, and a top skin contacting surface inclined to the bottom plane surface said top and bottom surfaces merging to a common edge forming an apex, a lateral side surface forming with the bottom surface an acute angled cutting edge extending in said bottom surface to said apex, a second member having a plane surface substantially co-incident with said plane bottom surface of the first member and adapted to contact therewith, a lateral side surface forming with said bottom surface, an acute angular cutting edge extending to said apex of the first 40 member, and means for moving the cutting edges relatively to each other, the cutting edges being so disposed in respect to each other when moving relatively to each other that they form an acute angle during their shearing action. 50

15. A razor comprising a movable skin contacting toothed member having top and bottom surfaces and cutting edges, the top surface acting as a skin contacting side flush with the skin the hairs of which are intended to be cut, a 55 stationary toothed second member on the off skin bottom surface of said first member and having cutting edges in registration with cutting edges of the first member at standstill of the first member, when the teeth are in registration with each other, the cutting edges of the respective members being inclined to each other during cutting action, and all of the cutting edges being substantially in one cutting edge plane, the second member having a skin contacting side flush with the skin the hairs of which are intended to be cut, said last-named side extending beyond the cutting edges, the skin contacting sides of the first and second members in any transverse section being in a single plane 60 inclined at an acute angle to the cutting edge plane, said single plane and the cutting plane bounding the top and bottom surfaces of the movable cutting member forming therebetween an acute angle at the tip edge of the cutting 70 75

member, and means for moving the first skin contacting member on the skin, and in respect to the second member to cut the hairs of the skin between the cutting edges, corresponding lateral sides of adjacent teeth of both cutting members upon alignment of the teeth being in a plane inclined to the cutting plane.

16. In a razor, a cutting member having four sides, two lateral sides, a top side, and a bottom side, the bottom side and one of the lateral sides forming a cutting edge extending to the end of the member, and the top side being in a plane forming with the plane passing through the bottom side an acute angle, the apex of which, formed by the cutting of these two planes, merges with the aforesaid end of the cutting edge, said top side being adapted to contact with the skin combined with a second cutting member having five sides, two lateral sides, two top sides and a bottom side, the two top sides having one side parallel with the bottom side of the first cutting member, and the other top side forming a skin contacting side and in the same plane as the plane passing through the top side of the first cutting members, the bottom side of the first cutting member and the parallel top side of the second cutting member being in a plane, the lateral sides of both members forming cutting edges movable in a cutting plane which is substantially coincident with the plane passing through the bottom side of the first cutting member and the parallel top side of the other cutting member, corresponding lateral sides of both cutting members upon alignment thereof being in a plane inclined to the cutting plane.

17. In a razor, the combination of a cutting member having teeth each having top and bottom sides tapering to a converging end, and having lateral sides, a cutting edge formed by the bottom side and one of the lateral sides and terminating at the converging end, said top side being adapted to contact with the skin, with a second cutter member having teeth each having a top side contacting with the bottom side of the teeth of the first cutter member, and having lateral sides, and having a cutting edge formed by one of said lateral sides with said top side, all of the cutting edges of the second cutter being substantially in the same cutting plane as the cutting edges of the first cutter, an extension beyond said top side of the teeth of the second cutter member and having a skin contacting side at an inclination to the top side and to the bottom side, the angle formed by the top side and inclined side being at the end of the cutting edge of the second cutter, said extension having lateral sides forming continuations of the lateral sides adjacent the top side, said inclined skin contacting side of the extension in any transverse section being in the same plane which passes through the top tapering side of the teeth of the first cutter member, corresponding lateral sides of adjacent teeth of both cutting members upon alignment of the teeth being in a plane inclined to the cutting plane.

18. In a razor, a cutter member having five sides, a top side, a bottom side, two lateral sides, and a side inclined from the top to the bottom side forming an apex, a cutting edge formed by one of the lateral sides and the bottom side, and terminating at the angle formed by the inclined side with the bottom side, the inclined side and the top side being adapted to contact with the skin, the bottom side with its cutting edge being

in a cutting plane, and the lateral sides being at an angular pitch to the cutting plane.

19. In a razor, the combination of a cutting member having teeth each having top and bottom sides tapering to a converging end, and having lateral sides, a cutting edge formed by the bottom side and one of the lateral sides and terminating at the converging end, said top side being adapted to contact with the skin, the cutting edges of the teeth being in a cutting plane, and the lateral sides being inclined to said plane, with a second cutter member having teeth each having a top side contacting with the bottom side of the teeth of the first cutter member, and having lateral sides, and having a cutting edge formed by one of said lateral sides with said top side, all of the cutting edges of the second cutter being substantially in the same cutting plane as the cutting edges of the first cutter, the lateral sides being inclined to the cutting plane, an inclined extension beyond said top side of the teeth of the second cutter member and having a skin contacting side at an inclination to the top side and to the bottom side, the top side and inclined side forming an angle at the end of the cutting edge of the second cutter, said extension having lateral sides forming continuations of the lateral sides adjacent the top side, said inclined skin contacting side of the extension being in the same plane which passes through the top tapering side of the teeth of the first cutter member, the lateral sides of the second cutter having the same angular pitch to the cutting plane as the lateral sides of the first cutter.

20. In a safety razor, a guard, a stationary member having teeth, and a skin contacting movable member having teeth mounted between the guard and the stationary member for movement relative to the stationary member, the outer skin contacting sides of the guard and members in any transverse section lying in substantially a common plane oblique to the plane of movement of the movable member to admit close proximity of the inner sides of the movable member teeth to the skin when the razor is in use and the teeth of the members having dull, non-sharpened edges at their outer sides and having adjacent contacting flat surfaces terminating in cooperating shearing edges at the sides of the teeth for cutting hairs entering the throats of the teeth by relative movement between the members, the lateral sides of the teeth of both members being at an angular pitch to the cutting plane, and the teeth when in registration in the same plane.

21. In a safety razor, a stationary skin contacting guard, a movable skin contacting member having teeth at its edge and a stationary skin contacting member having teeth at its edge, said guard and members being disposed in superposed relation, the skin contacting surfaces of the guard, movable member, and stationary member in any transverse section being in a single plane oblique to the plane of movement of the movable member to form a substantially linear contact with the skin, the abutting inner sides of the teeth of the members being flat and terminating in shearing edges for cutting hairs by a shearing action upon relative movement of the teeth, the lateral sides of the teeth of both members being at an angular pitch to the cutting plane, and in the same plane when the teeth are in registration.
